INVENTOR:
JOHN SCHULDE.
By Harry A. Bernau
ATTORNEY.

UNITED STATES PATENT OFFICE.

JOHN SCHULDE, OF ST. LOUIS, MISSOURI.

REFRIGERATOR.

Application filed April 31, 1924. Serial No. 705,904.

To all whom it may concern:

Be it known that I, JOHN SCHULDE, a citizen of the United States, residing at 3553 Vista Street, St. Louis, in the State of Missouri, have invented certain new and useful Improvements in Refrigerators, of which the following is a specification.

My invention has relation to improvements in refrigerators and consists in the 10 novel features of construction more fully set forth in the specification and pointed out in the claims.

The object of the present invention is to provide a refrigerator of the display case 15 type with an ice chamber preferably at each end, and a storage chamber having means for facilitating the air circulation throughout its extent, which is very important for preserving perishable foodstuffs.

20 A further object of this invention is to provide an ice container that may be easily moved out of its chamber for a fresh supply of ice and as easily moved back in place again. Further and other advantages will 25 be better apparent from a detailed description of the invention in connection with the accompanying drawings in which—

Figure 1 is a combination rear elevation and vertical longitudinal section of the refrigerator; Fig. 2 is an enlarged middle vertical longitudinal section through one-half of the refrigerator and its ice container; Fig. 3 is an enlarged horizontal longitudinal section on the line 3—3 of Fig. 1; Fig. 4 is a 30 vertical cross-section on the line 4—4 of Fig. 3; Fig. 5 is a sectional detail of the return flue inlet taken on the line 5—5 of Fig. 2; Fig. 6 is a top plan detail of one of the ice container rails and extension thereof; Fig. 7 is a detail view showing one of the corner angles on which the extension rail is pivoted; and Fig. 8 is a cross-sectional detail taken on the line 8—8 of Fig. 7.

45 Referring to the drawings, A represents the refrigerator case having an ice chamber C at each end and a storage or provision chamber B in the middle, there being doors D, D in the rear wall of the ice chambers and doors D', D' in the rear wall of the provision chamber. The provision chamber is also equipped with the usual glass panels at the front.

There are two vertical angle members 1, 1, secured to the rear wall α of the ice chamber

ber, said angle members extending slightly 55 inside the door opening O.

A rail 2 is secured at one end to each angle member 1, a short distance from the top thereof, the other end of the rail being secured to a strip 3 fastened on the front 60 wall α' of the ice chamber. There is also an extension rail 4 pivotally connected to each member 1 in line with the rail 2 so that when the rail 4 is raised to a horizontal position it will form a continuation of rail 65 2 (dotted Fig. 4). In order to hold the rails 4, 4 in their horizontal position a brace bar 5 is pivotally connected on the outside 70 of each near the free end thereof, said brace bar 5 being spaced from the rail 4 at the pivot 6 by a washer 7 sufficiently so that the bar 5 may operate through a slot 8 in the angle member 1. The free ends of rails 4, 4 are connected by a rod 9 so they will move together. When the rails 4, 4 are lowered 75 to vertical position the brace bars 5 extend back into the ice chamber C, and are supported by pins 10, 10 in a horizontal position. Now, on raising rails 4, 4 to a horizontal position they will pull the brace bars 80 5, 5 out of the ice chamber through the slots 8, 8 in members 1, 1, and when the rails are in a horizontal position their inner ends will abut the adjacent ends of rails 1, 1 thus arresting further movement, and at 85 the same time the notches n , n , in the lower ends of bars 5, 5 will drop onto the bottom edge of slots 8, 8. The extension rails are now firmly held in extended position.

An ice container 11 is positioned within the ice chamber C said container having a pair of spaced rollers 12, 12 on each side whereby it is rollingly supported on rails 2, 2. Within the container 11, and extending from side to side thereof at the bottom are two inverted V-shaped bottom members 11', 11' spaced from the sides and from each other, the object of said bottom members being to support the cracked ice and salt placed within the container and at the same time to permit the brine to drain out of the container into the brine tank 13 subjacent thereto. Within the ice container is an air cooling flue 14, said flue having an air inlet opening 15 centered near the top of the container and an outlet opening 16 centered near the bottom of the container said outlet being considerably larger than

100

105

the inlet, both openings being in the side of the container toward the provision chamber B. The flue is gently curved from the inlet into the container somewhat past the middle thereof, and then curves back to the outlet, at the same time uniformly increasing in size so that its general shape is that of a cornucopia, although a cross-section taken on any plane is rectangular. A baffle 17 extends across the interior of the refrigerator in front of the outlet opening 16 and forms a division line between provision chamber B and ice chamber C, however there is a space 18 between the top of the baffle and an intermediate shelf 19, and a space 20 between the bottom of the baffle and the brine tank, said spaces forming passages for the cold air as it issues from the flue 14, and the baffle 17 serving to direct the cold air toward the shelf 19 and a second shelf 21 near the bottom of the provision chamber B.

At the middle of the top of the provision chamber B is an air collector 22, said collector extending across the chamber and having an elongated inlet opening 23 in each side wall thereof. The ends of collector 22 connect with air conduits 24, 24 extending along the sides of the provision chamber and leading to a box 25 supported by the inner rail 2 said box also receiving the inlet 15 of flue 14. The side wall 25 of box 25 toward the ice chamber door D is open so that the inlet end of flue 14 may pass freely out of the box when the ice container is rolled from its chamber.

Resting on the bottom of the provision chamber is an enclosed brine circulating tank 26 which receives the brine overflowing from the lip 27 of the tank 13, said tank having a raised bottom 28 and a top wall 29 through both of which pass a series of flues 30 through which the air may circulate as it moves through the chamber B. The surfaces of the flues are kept cold by the brine within tank 26 hence these flues serve as auxiliary cooling means for the air. The end of brine tank 26 farthest from the ice chamber C is provided with an overflow pipe 31 through which the brine discharges into basin 32 which is connected with the sewer not shown).

In operation the ice container 11 is filled with cracked ice and salt, which operation is easily accomplished by opening door D, raising extension rails 4 as heretofore described and rolling the ice container out of chamber C. The container 11 is then pushed back into place and door D closed. As the flue 14 becomes cold the air within it will cool and pass down through said flue, discharging against baffle 17 where the cold air divides some passing under shelf 19 through space 18 and some passing under

shelf 21 through space 20. This complement of cold air will be advanced through the provision chamber by that coming behind it, and as it passes along its temperature will naturally rise, the air then rising in the provision chamber. As this warmer air approaches the air collector 22 it will be sucked into it through opening 23, since there is a circulation created in the conduits 24 by the cooling flue 14, and this warmer air will then be conducted back to the cooling flue 14 for recooling.

When the ice container 11 is charged with a fresh supply of ice some of the smaller pieces are liable to fall through the spaces between bottom members 11', 11'. In order that this ice may not fall on the floor I provide a tray 33 hinged to the bottom of members 1, 1 said tray being lowered to the dotted position (Fig. 4) when the container 11 is being charged. When the tray is raised before closing door D these pieces will be dumped into brine tank 13.

Having described my invention, I claim:

1. In a refrigerator comprising a case having a provision chamber and an ice chamber, an ice container in said ice chamber, an air cooling flue within the ice container, said flue having an inlet near the top of the container and opening toward the provision chamber, and an outlet near the bottom of the container, extending across substantially two-thirds the width of the container, and opening toward the provision chamber, a shelf within the provision chamber near the bottom thereof, a shelf intermediate the bottom shelf and the top of said chamber, and a baffle plate spaced from the ice container and in front of the air flue outlet for deflecting the cold air issuing from said outlet toward said shelves.

2. In a refrigerator comprising a case having a provision chamber and an ice chamber at one end thereof, an ice container in said chamber, an air cooling conduit within the ice container having an air inlet near the top thereof and an air outlet near the bottom, both inlet and outlet opening toward the provision chamber, a warm air collector extending across the provision chamber at the top thereof and at the end farthest from the ice container, said collector having an intake opening in one side, and air conduits leading from the ends of the collector to the inlet opening of the aforementioned cooling conduit.

3. In a refrigerator comprising a case having a provision chamber and an ice chamber at one end thereof, an ice container in said chamber, an air cooling conduit within the ice container having an air inlet near the top thereof and an air outlet near the bottom, both inlet and outlet opening toward the provision chamber, a warm air

collector extending across the provision chamber at the top thereof and at the end farthest from the ice container, said collector having an intake opening in one side, and air conduits leading from the ends of the collector to the inlet opening of the aforesaid cooling conduit, and a brine circu-

lating tank in the bottom of the provision chamber, said tank having air circulating flues passing through it.

10 In testimony whereof I hereunto affix my signature.

JOHN SCHULDE.
